[57] CLAIM

The ornamental design for a broiling grill, as shown and described.

DESCRIPTION

FIG. 1 is a perspective view of a broiling grill showing our new design, the grill being in a high position with the grill handles extending downwardly;
FIG. 2 is a top plan view thereof;
FIG. 3 is a bottom plan view thereof;
FIG. 4 is a rear elevational view thereof;
FIG. 5 is a front elevational view thereof;
FIG. 6 is a left side elevational view thereof, the right side being a mirror image; and,
FIG. 7 is a perspective view thereof, the grill being in a low position with the grill handles extending upward.

Fig.1.

Fig.2.

Fig.3.**Fig.4.**
